UNITED STATES PATENT OFFICE.

SIDNEY ERNEST KELLEY, OF WESTFIELD, MASSACHUSETTS.

GAME APPARATUS.

1,269,941.

Specification of Letters Patent. Patented June 18, 1918.

Application filed March 31, 1917. Serial No. 153,980.

To all whom it may concern:

Be it known that I, SIDNEY E. KELLEY, a citizen of the United States of America, residing at Westfield, in the county of Hampden and State of Massachusetts, have invented a new and useful Game Apparatus, of which the following is a specification.

My invention relates to improvements in apparatus designed more especially for playing the game of indoor foot-ball, and consists essentially of a board and markers mounted and movable thereon, and an indicating device in the form of a dial and pointer, all being of novel construction, as hereinafter set forth.

The game board is made to simulate a "gridiron" or foot-ball field, by having marked thereon divisions indicating the number of yards on either side of the center, with certain other designating matter, including means whereby the necessary two opposite or contending sides, representatives of the same number of teams, are clearly represented or indicated.

The dial determines, with the aid of its pointer, the character of the moves to be made with the markers on the board, the game as played by the two sides being directed by said dial and pointer.

The respective sides play this game alternately, and the manner of playing the same is a fair simulation of that in which is played the outdoor game of foot-ball.

The primary object of my invention is to produce an especially simple and inexpensive game apparatus, of the class specified above. The board with the markers included and the indicating device are both not only simple structurally, but of a character that makes easy the playing of the game, so that children and persons of ordinary intelligence can understand and use the same practically and satisfactorily.

A further object is to provide a game board of this kind with markers which can be easily and quickly applied or mounted in place on the board, and which then are not liable to become detached and mislaid or lost, while at the same time being readily movable and adapted to indicate to the best advantage the results of the plays made by the players in accordance with the indications obtained from the dial and pointer.

Still another object is to provide the aforementioned game board with clear, positive, and fixed designations of the two opponents or

players, "Harvard" and "Yale" indices being here used for this purpose, merely as an example, inasmuch as any other indices may as well be employed.

Other objects and advantages will appear in the course of the following description.

I attain the objects and secure the advantages of my invention by the means illustrated in the accompanying drawings, in which—

Figure 1 is a top plan of the game board with its markers; Fig. 2, an enlarged cross-section through said board, showing the "ball" marker and one of the "linemen" markers in elevation, one arm of the cross support, lateral brace, or carrier for the ball being broken off to disclose the arm of said lineman marker behind; Fig. 3, an enlarged end elevation of said ball marker, and, Fig. 4, a top plan of the indicating device.

Owing to the length of the board the same is shown in two sections, with the right-hand section under the left-hand section and connected by arrow-tipped dot-and-dash lines, in Fig. 1.

Similar reference characters designate similar parts throughout the several views.

A game board is represented at 6 and an indicating device at 7. I will first describe the board 6 and then the indicating device 7.

The board 6 is long and narrow and may have tapered terminals 11—11. Longitudinal grooves 12—12 are made in the side edges of the board 6, or in the parallel portions of such edges. On the upper surface of the tapered terminals 11 are delineated dissimilar characters or insignia to differentiate the two sides or the two players of the game, "H" and "Y" and two pairs of banners being here employed as such insignia, with the "H" on one terminal and the "Y" on the other terminal. The banners at the two ends may be in appropriate contrasting colors, as crimson (red) and blue in this case. Goals are indicated at 13—13 on the terminals 11, although these are not necessary. A gridiron or foot-ball field 14 in miniature is laid out or delineated on the upper surface of the board 6 between the goals 13. This field is divided by long cross lines into "ten-yard" lengths indicated by the numerals 10, 20, 30, 40, 50, from each end to the center, the center line being 50, and by short cross-lines 15 into "five-yard" lengths. A line of spots or rectangles 16 extends through the center of the field 14,

The rectangles 16 are in spaced relationship, and their number and arrangement are such that each is assumed to be one yard from the next adjacent rectangle in either direction. The five-yard space next to the H end of the field 14 is marked "5 yd loss Yale", so too is the five-yard space inside of and adjacent to the 10-yard line at that end, and the five-yard space next to the Y end of said field is marked "5 yd loss Harvard", likewise the five-yard space inside of and adjacent to the 10-yard line at said last-named end; while said first-named 10-yard line is marked "5 yd loss Harvard," and said second-named 10-yard line is marked "5 yd loss Yale". The space outside of and adjacent to each 30-yard line is marked "Field goal zone". The significance of the aforesaid markings is obvious to anyone at all skilled in the foot-ball game.

Three transverse markers are mounted to slide in either direction on the board 6. Said markers comprise two "linemen" markers 17 and a "ball" marker 18, the latter being between the two former.

The linemen markers 17, which are usually made of wire, extend across the field 14 and the board 6. At each end of each marker 17 is an angular arm 19 which extends down on one side of the board 6 above the groove 12 in that side or edge of said board, and enters said groove. It will be seen, therefore, that the arms 19 hold the markers 17 in place on the board whether said markers be stationary or moved. One of the linemen markers 17 is employed by the opponent of the player who is manipulating the ball marker 18, and the functions of said markers are similar to those of actual linemen in the field game.

The ball marker 18, besides a part that extends across the board 6, like the linemen markers 17, and has at each end an angular arm 21, similar to the arms 19 only longer in its vertical portion, to engage one or the other of the slotted edges of said board, comprises a "ball" 22 which is mounted centrally on said part and provided at the ends with downwardly - projecting feet 23—23. The feet 23 are in the same vertical plane with and travel over the rectangles 16 and so point out clearly the position of the ball 22, the foot which is in advance in the direction of travel being the one employed by the player who is operating the ball marker. The feet 23 rest on the board 6 and so support the ball 22 from below, while the member upon which said ball is mounted holds said ball against lateral movement and prevents the same from being turned in such a manner as would divert said feet from their proper course over the rectangles 16. The ball 22 is elevated somewhat from the board 6 by the feet 23, wherefore it is necessary that the vertical portions

of the arms 21 be of sufficient length to accommodate the transverse part of the marker 18 to said feet and ball and at the same time permit the inturned parts which form the bases of said arms to enter and slide in the slots 12. The several parts and members of the ball marker, except the ball itself, may be made of wire.

It is now seen that the ball and linemen markers extend across and embrace the board, yet can be moved readily in either direction, and that said markers are always in operative position. The markers 17 and 18 can easily and quickly be slipped on and off of the board 6 at the ends of the parallel-sided portion of said board.

The indicating device 7 has a dial 24 delineated and a pointer 25 mounted theron as parts thereof. The pointer 25 is pivoted in the center of the dial 24 at 26. The dial comprises a plurality of peripheral spaces in which are arranged ciphers, digits, and tens, and a diametral line 27 divides the large central space inside of said peripheral spaces into halves, and a radial line 28 divides one of the semi-circular spaces thus produced into two equal parts. The following controlling data appears on the dial: In the undivided semi-circular space "Goal from touchdown made—forward pass complete—field goal made"; in one of the quarter-circle spaces "Forward pass incomplete" and in the other quarter circle space "Forward pass intercepted"; and in the combined quarter-circle spaces "Goal from touchdown missed" and "Field goal missed." This controlling data gives effect to the characters in the peripheral spaces. Said characters or the digits and tens thereamong designate yards.

In playing the game with the hereinbefore described board, markers, and indicating device, the players take turns, one spinning the pointer 25 and moving the ball marker 18, each move of said marker being determined by the position of said pointer on the dial 24 each time the former comes to rest, until it becomes the turn of the other player to spin said pointer and move said marker. The ball marker 18 is started each time from the 50-yard line, with the foot 23 which is forward in the direction of travel resting on said line. The linemen marker 17 which is ahead of the ball marker 18, in the direction of travel of said ball marker, is the one used, the same being moved by the opponent of the player who is manipulating said ball marker. The Y player or "Yale" operates the ball marker in the half of the field 14 that is between the center of the board and the H terminal thereof starting from said center, and the H player or "Harvard" moves the linemen marker that is between said terminal and said ball marker in either direction or forward and

backward as required. When it becomes the turn of the H player to move the ball marker he also starts at said center, but operates in the other half of said field, 5 and the Y player operates the other linemen marker.

As already stated the game played with this apparatus is conducted in accordance with ordinary foot-ball rules, which are so 10 well understood that it is not deemed necessary to encumber this specification with even an outline of the same. The method of scoring is included in said rules and also applied here.

15 I am aware that various game boards and associated or correlated devices have before been employed for playing the game of indoor foot-ball, and do not, therefore, seek to claim broadly means for playing such 20 game.

What I do claim as my invention, and desire to secure by Letters Patent, is—

1. In a game apparatus, a board having thereon the simulation of a foot-ball field, 25 and a marker spanning and slidingly arranged on said board over said field.

2. In a game apparatus, a board having thereon the simulation of a foot-ball field, 30 and a ball marker slidingly arranged on said board, said marker consisting in part of a foot to ride over said field and serve as a pointer.

3. In a game apparatus, a board having thereon the simulation of a foot-ball field, 35 and a marker slidingly-arranged on said board, said marker consisting in part of a ball provided with feet to ride over said field and serve as pointers.

4. In a game apparatus, a board having 40 thereon the simulation of a foot-ball field, and ball and linemen markers spanning and slidingly-arranged on said board over said field.

5. In a game apparatus, a board having 45 thereon the simulation of a foot-ball field, a ball marker and linemen markers spanning and slidingly-arranged on said board over

said field, said linemen markers being on opposite sides of said ball marker.

6. In a game apparatus, a board having 50 thereon the simulation of a foot-ball field, and also having longitudinally-grooved side edges, and a marker spanning said board and provided with arms adapted to engage such grooved edges, said marker being 55 adapted to slide over said field.

7. In a game apparatus, a board having 60 thereon the simulation of a foot-ball field, and also having longitudinally-grooved side edges, and a marker which spans said board and engages said grooved edges, and is provided with feet which are adapted to serve 65 as pointers relative to said field.

8. In a game apparatus, a board having 70 thereon the simulation of a foot-ball field, and also having longitudinally-grooved side edges, and a marker comprising a member which spans said board and engages said grooved edges, a ball mounted on said member, and feet extending from said ball into 75 position to serve as pointers relative to said field.

9. In a game apparatus, a board having 80 thereon the simulation of a foot-ball field, such simulation comprising a series of transverse yard lines, and a longitudinally-extending row of yard spots, and a ball marker spanning and slidingly-arranged on said board, and consisting in part of feet to ride over said lines and spots.

10. In a game apparatus, a board having 85 thereon the simulation of a foot-ball field, such simulation comprising a series of transverse yard lines, and a longitudinally-extending row of yard spots, and a ball 90 marker spanning and slidingly-arranged on said board, and consisting in part of feet to ride over said lines and spots, the field zones and yards lost to both sides being denoted on said field.
